UNITED STATES PATENT OFFICE.

HARRY G. WEBSTER, OF CHICAGO, ILLINOIS, ASSIGNOR TO MILO G. KELLOGG, OF CHICAGO,
ILLINOIS.

TELEPHONE SYSTEM.

931,904.

Specification of Letters Patent. Patented Aug. 24, 1909.

Application filed July 27, 1906. Serial No. 328,012.

To all whom it may concern:

Be it known that I, HARRY G. WEBSTER, a citizen of the United States, and resident of Chicago, county of Cook, and State of Illinois, have invented certain new and useful Improvements in Telephone Systems, of which the following is a specification.

My invention relates to telephone exchange systems and particularly to that type in which link-conductors are interchangeably associated with the subscribers' lines, mechanism being provided for each subscriber's line, which is automatically actuated when the receiver is taken for use to connect the subscriber's line to an idle link-circuit and cause the display of a calling signal associated with a manually controlled terminal of the link-circuit.

One object of my invention is to provide, in a structure of this character, novel means for securing the proper connection and disconnection of the subscriber's line and the link-conductor in a structure characterized by simplicity and economy of manufacture and positive and efficient operation.

A further object of my invention is to provide means whereby, during the time a calling signal is displayed in front of an operator, no other idle link-circuits at her position will be selected. This results in rendering the operator's position busy as long as she has an unanswered calling signal displayed at her position.

In accordance with my invention, I provide for each subscriber's line a traveling switch which is preferably a rotary switch adapted to carry its movable contacts in one direction only. This switch is rotated by step-by-step mechanism, preferably actuated by current from a pulsating generator. The switch is provided with three moving contacts or wipers which constitute the terminals of the circuits individual to the line and with fixed contacts adapted for engagement with the wipers, as they are rotated, and these fixed contacts are connected to wires individual to the various link-conductors. These link-conductors terminate preferably in cords and plugs at the various operators' positions of a multiple switchboard, and the several lines are provided with multiple jacks at the various multiple sections. The wipers of the traveling switch have a normal position in which they do not engage any of the fixed contacts of the switch, and when rotated, will engage preferably, first, the contacts

connected to a link-circuit at the first operator's position; then, contacts connected with a link-circuit at the second operator's position; then those leading to the third operator's position, and so on; and these fixed contacts are multiply connected to similar switches individual to other subscribers' lines in a group. The other link-circuits terminating at the first, second, third and other operators' positions, may be similarly connected to the rotating switches of lines in other similar groups, the arrangement being such that if the link-conductor connected to the first terminals of a particular group of switches, and terminating in front of the first operator at the switchboard, be busy, the switch will step ahead to the second terminal leading to a second operator, and so on until an idle link-circuit is reached, when it will come to rest and the operation of associated mechanism will connect the line limbs to the talking conductors of the link-circuit. At the same time, a calling signal, associated with the link-circuit, will be displayed; and after ascertaining what connection is desired, the operator inserts the plug into the multiple jack of the desired line. When conversation is finished, the removal of the connecting plug causes a further rotation of the switch to restore its wipers to their normal position.

To secure the proper operation of the apparatus and circuits, I provide two relays individual to the subscriber's line, and in this respect my system differs from others heretofore proposed. One of these relays may be called a "cut-off relay", and its operation serves to connect the line limbs to the wipers of the switch when the link-circuit is selected. The other relay, which may be called a "line relay", serves, among other functions, to start and stop the traveling switch during the selection and disconnection of the link-circuit.

In further accordance with my invention, I associate with the calling signal of the link-circuit, mechanism actuated during the display of any calling signal, which serves to make all idle cord circuits of the operator's position artificially busy, and this mechanism is preferably controlled by a relay common to all of the calling signals of that position. It is thus evident that as long as a calling signal remains displayed in front of an operator, no further link-circuits on her position can be selected and therefore but

one calling signal at a time can be displayed before her.

My invention will be more fully understood from the accompanying drawing in which—

A and B represent substations connected to a central office in accordance with a preferred form of my invention; the apparatus associated with the line A being illustrated in complete diagram, and that associated with B being completely shown except for the traveling switch and its wipers and contacts. The substations are provided with the usual bell and condenser in a permanent bridge of the line limbs, the receiver *r* and transmitter *t* being included in a normally open bridge closed at the upper contact of the switch-hook *h*. The limbs 1 and 2 extend to the central office and are there connected to the terminals of a battery C. Each line is provided with a line relay 3 and a cut-off relay 4 and with a rotary switch S. This switch is actuated by a motor magnet M in response to current from the pulsating generator G, the switch being diagrammatically indicated as having a ratchet-wheel 5 carried on a shaft 6, which shaft also carries the wipers *a*, *b*, *c*, the first two mentioned wipers being associated with limbs 1 and 2 respectively, and wiper *c* being associated with a local or private circuit. Wiper *a*, when rotated by the operation of magnet M and ratchet-wheel 5, engages contact pieces *a'*, *a''*, *a'''*; wiper *b* at the same time engages contacts *b'*, *b''*, *b'''*; and wiper *c* at the same time engages contacts *c'*, *c''*, *c'''*, in the order indicated, and other contact pieces correspondingly throughout the rotation. These contact pieces are multiply connected to corresponding contact pieces of other switches in the same group of lines, such another switch being indicated at S', all of the contact pieces *a'*, *b'* and *c'* being also connected to the wires of a link-circuit terminating in a cord and plug at the first operator's position, the contact pieces *a''*, *b''*, *c''* being connected to the wires of a link-circuit terminating at a second operator's position, and so on through all of the contacts of the switch. Wipers *a* and *b* are indicated as having narrow terminals, and in rotating disengage one contact before engaging the next, while wiper *c* has a wide terminal and engages one contact before disengaging the previous one. The switch is also provided with contacts 10—11, which are in engagement except when the switch is in the normal position—that of the diagram—and with contacts 12—13 which are out of engagement except when the switch is in its normal position.

When the subscriber desires to initiate a call, the removal of his receiver closes a circuit which may be traced from the active terminal of battery C through winding 14 of relay 3, thence through contact 15 and

armature 16 of relay 4, through the line limbs and substation, then by wire 17 to contact 12—13 of the switch S and to ground through contact 18 and armature 19 of relay 4. This current operates relay 3, 70 producing the following condition: The attraction of armature 20 disconnects wiper *b* from the sleeve side of the jack circuit at contact 21 and connects the sleeve contact of the jack and the winding 23 of relay 4 to the active terminal of the battery C, through resistance 24 at contact 25. The resistance 24 is relatively high and serves to prevent the operation of relay 4 at this time, while providing the proper potential at sleeve contact 26 of the jacks to give a busy indication. The actuation of armature 91 disconnects limb 2 from wire 93 which leads through armature 46 and contact 47 of relay 4 to wiper *a*. The actuation of armature 27 connects winding 14 of relay 3 to the private wiper at contact 28, the resistance 29 being included in circuit between the wiper and contact. The attraction of armature 30 completes a circuit for motor magnet M and generator G and the switch takes one step ahead. In its normal position, the wipers of the switch do not engage any of the fixed contacts thereon. As the first step is made, wipers *a* and *b* engage contacts *a'* and *b'* respectively; but the wipers being at this time disconnected from the line limbs and from the central battery, no interference results in case the link-circuit corresponding to these contacts is in use for conversation. At the same time, wiper *c* engages contact *c'*, contacts 10—11 of the switch come into engagement, and contacts 12—13 are disengaged. If the link-circuit corresponding to contact *c'* be busy, contact *c'* will be connected to ground and the switch will continue in its travel until an idle link-circuit be reached, as will be subsequently described. Assuming the link-circuit corresponding to *c''* to be idle, no circuit will be completed through the engagement of the wiper *c* with the contact, as the wires leading from the contact *c'*, *c''*, *c'''*, are open or disconnected from the central battery during the idle condition of the cord. This being the case it will be seen that the circuit energizing relay 3, previously traced, has been interrupted at contacts 12—13 of the switch by the resulting disconnection of limb 2 from the return side of the battery or ground. 110 Relay 3 is thus deenergized, its contacts assume their normal position, the retraction of armature 30 interrupting the circuit of motor magnet M and preventing the further rotation of the switch. The retraction of 115 armature 20, engaging contact 21 connected to wiper *b*, closes, therefore, a circuit which may be traced as follows: from the active terminal of battery C, through winding 31 of relay 32 and strand 33 of the cord, and 120

130

through winding 34 of the same relay, contact 35 and armature 36 of relay 37, contact 38 and armature 39 of relay 40, and armature 39 of relay 40, and armature 41 and contact 42 of relay 32, and thence through relay 43 to the same strand 33 of the cord circuit, thence to contact b^3 , wiper b , contact 21 and armature 20 of relay 3 and through winding 23 of relay 4 to the return side of the battery. The windings 31 and 34 being at this time in multiple differential relation and having a substantially equal number of turns, relay 32 remains unenergized, while cut-off relay 4 is operated.

The operation of relay 4 disconnects limb 1 of the line from winding 14 of relay 3 at the contact 15 and connects it to the circuit just traced at the contact 45, thus completing the talking circuit for the sleeve strand of the cord; and the attraction of armature 46, engaging contact 47, completes the circuit of line limb 2, through wire 17, armature 91, contact 92, wire 93, armature 46, contact 47, and wire 7 to wiper a , contact a^3 and tip strand 48 of the cord circuit. Additional current will now flow from battery C, through the circuit (previously traced) of relay 32 and strand 33, through the two line limbs and substation and thence by wire 7, wiper a and contact a^3 , strand 48 and the winding of relay 37 to the return side of the battery. This current energizes the substation transmitter and operates relay 37. The attraction of armature 36 interrupts the circuit through winding 34 of relay 32 at the contact 35, and momentarily connects strand 33 to ground through relay 43, contact 42 and armature 41 of relay 32, armature 39 and contact 38 and armature 36 and contact 44 of relay 37, and the resistance of relay 43 will prevent the retraction of armatures 16 and 19 of relay 4, in case relay 32 operates sluggishly at this time. The attraction of armature 40, engaging contact 50, completes a circuit of signal lamp 51 which may be traced from the active terminal of battery C, through the lamp, armature 49, contact 50, relay 52, contact 53 and lever 54 of the listening-key k , and thence through contact 55 and armature 56 to the return side of the battery, causing the illumination of the lamp and energizing relay 52, which is a common relay and controls the circuit of the pilot lamp 99. The interruption of the circuit through winding 34 of relay 32 allows this relay to be energized by current flowing through winding 31. The consequent attraction of armature 41 at contact 42 maintains the interruption of the circuit through winding 34 and relay 43 as long as the relay remains energized, and the engagement of armature 41 with contact 57, completes a direct earth connection from private contact c^3 , through contact 57, armature 41, armature 39 of relay 40, contact 38 and armature 36 and con-

tact 44 of relay 37; and it is the presence of an earth connection to contact c^3 which produces the "busy" condition of the link-conductor. A further result has been produced by the energization of pilot relay 52. The engagement of its armature 58 and contact 59 causes the energization of relay 60 which is also common to the position.

Relay 60 has a multiplicity of contacts, the armature 61 being connected to the private contact c^3 for the first cord circuit of the position, the armature 62 being connected to the corresponding contact for the second cord, the armature 63 to the corresponding contact for the third cord, and so on, and the attraction of the armatures connects these private contacts to ground through the resistances 64, 65 and 66 respectively; these resistances being so proportioned that the ground connection thus secured will produce the required busy condition of all idle cords without interfering with the other operations of the structure. The result of this arrangement is that as long as the lamp 51 remains illuminated, all cords upon the operator's position will be in the busy condition and she can receive no further calls until, in answering that of lamp 51, she depresses her listening-key k and thus interrupts the circuit of the lamp and relay 52 at lever 54 and contact 53. The circuit is now in condition for the operator to communicate with the subscriber. Learning that subscriber B is desired, she tests in the usual way with the plug O. It is to be noted here that when subscriber A initiated the call, and during the rotation of his switch, his spring-jack contact 26 was connected to battery C through the high resistance 24 to give a busy indication by the engagement of armature 20 and contact 25 of relay 3. Likewise, the establishment of the circuit through winding 23 of relay 4 has maintained the necessary potential to give a busy test at the jack contact 26; and as will be subsequently described, the necessary potential is maintained during the process of disconnection while the switch is returning to normal.

Assuming the line of subscriber B to be idle, the operator inserts the calling plug O into the jack j and actuates her ringing-key k' . Current will now flow from battery C to contact 26 of the jack and through winding 23 of relay 4 to the return side of the battery, operating the relay and maintaining its armatures attracted during the process of ringing. The actuation of armature 16 disconnects limb 1 from relay 3 at contact 15, thus preventing any energization of relay 3 or consequent operation of the rotating switch associated with line B during the progress of the connection, and connects limb 1 to contact 26 of the jack at contact 45, while the actuation of armature 46 con-

nects limb 2 to contact 67 of the jack at contact 47 of relay 4. Ringing current is thus supplied to the line from generator G' in the usual manner. Upon the restoration of the 5 ringing-key, current will flow from battery C, through the winding of relay 40, the cord strand, plug O, contact 26, and winding 23 of relay 4, thus maintaining the energization of the relay and energizing the relay 40. 10 The ensuing actuation of armature 39 of relay 40 substitutes a ground connection at contact 68 for that previously existing at contact 44 of relay 37; the attraction of armature 56 interrupts the circuit of lamp 15 51 and relay 52 at contact 55 so that the release of the listening-key does not cause the subsequent illumination of lamp 51; and the actuation of armature 69 disconnects the tip of the plug from the testing circuit to 20 strand 70 at contact 71 in the well known manner. When the subscriber responds, additional current will flow through the relay 40, strand 72 of the cord circuit, contact 26 of the jack, contact 45 and armature 16 of relay 4, the line limbs and substation, thence through armature 46 of relay 4, contact 47, jack contact 67, strand 70 and relay 73 to ground. The initial attraction of armature 56, engaging contact 74 of relay 40, completed the circuit of supervisory lamp 75 upon the restoration of the ringing-key, causing the illumination of the lamp; and current, which flows through the substation and relay 73 when the subscriber responds, energizes relay 73 to extinguish the lamp in the well known manner.

When subscriber B hangs up his receiver at the conclusion of conversation, the consequent deenergization of relay 73 causes the 40 illumination of lamp 75. Likewise, the restoration of the receiver at station A allows the retraction of the armatures of relay 37; that of armature 49 causing the illumination of lamp 51, while that of armature 36, which is now in open circuit at contact 38, produces no further result. The illumination of the two lamps constitutes the disconnect signal, and the operator removes the plug O, thus deenergizing the relay 4 and 45 allowing its contacts to return to normal, and deenergizing relay 40 to produce a new circuit condition, it being borne in mind that relay 32 is still energized by current flowing through its winding 31 and to the return side of the battery through the winding 23 of relay 4 of line A. Armatures 56 and 69 assume their normal positions without further result, but the retraction of armature 39 connects battery to private contact c³ to produce the condition of the release. A circuit may now be traced from battery C, through winding 34, contact 35, armature 36, contact 38, armature 39, armature 41 and contact 57 to contact c³ of the 55 switch, thence by wiper c through resistance

29, winding 76 of relay 3, winding 77 of relay 4, contacts 10-11 of the switch and contact 78 and armature 19 of relay 4 to the return side of the battery. This current serves to maintain the energization of relay 4 and to 70 energize relay 3, but is of insufficient strength to release relay 32 or reverse its polarity. The attraction of armature 27 of relay 3 connects winding 14 in serial relation with winding 76 at contact 28, and current now flows 75 through the two windings, through winding 77 of relay 4, and contacts 10-11 of the switch to the return side of the battery at contact 78 and armature 19 of relay 4, and this circuit is maintained until the switch reaches its normal position and separates contacts 10-11. The attraction of armature 20 interrupts the circuit of relay 32 through winding 23 of relay 4 at contact 21, and the engagement of armature 20 with 80 contact 25 provides the necessary potential at contact 26 of jack j to give a busy test during the process of release. The attraction of armature 30 now completes a circuit of motor magnet M and generator G, which 85 causes the switch to continuously rotate until relay 3 is deenergized by the disengagement of contacts 10 and 11 when the wipers reach their normal position. During 90 this releasing operation, the connection of wiper a to wire 17 stands open at contact 92 and armature 91, and no current flow will result from the engagement of this wiper with the contacts a', a², a³ of busy or idle cord circuits. The wiper b standing open at this 100 time at contact 21, no interference results from its engagement with contact b', b², b³ of busy or idle link-conductors, and the presence of resistance 29 in circuit with wiper c and wire 9 prevents the engagement 105 of wiper c with the contacts c', c², c³ of busy cords from short circuiting winding 77 of relay 4, which might result through the direct earth connection of contacts c', c², c³ of such busy cords. 110

Referring again to the initial actuation of the switch which takes place in response to the removal of the receiver from the switch-hook, it has been pointed out that if the cord circuit associated with a contact c', c², c³, be 115 idle, the wire leading from this contact will stand open at contact 57 of relay 32 and at armature 61 of relay 60, and the switch would come to rest through the interruption of the circuit of winding 14 of relay 3. 120 Wiper c is provided with a broad terminal and, as the switch makes its first step, will engage contact c' during the initial portion of the motion. If the cord circuit associated with contact c' be busy, the wire leading from this contact will be connected to ground either through armature 41 of its relay 32 or through a resistance 64 of the common relay 60. This being the case, a circuit may be 125 traced from battery C through winding 14 130

of relay 3, armature 27, contact 28, resistance 29, wiper *c* and contact *c'* to the return side of the battery; and the current flowing through this circuit maintains the attraction 5 of the armatures of relay 3 and the switch takes a second step. The wiper *c* in its rotation engages contact *c*² before disengaging contact *c'*; and if the cord circuit associated with contact *c*² be busy, a similar circuit for 10 winding 14 of relay 3 is found and the switch thus continues to rotate until an idle cord circuit is reached.

In case limb 1 of the line become accidentally grounded, it is evident that the 15 switch will rotate without selecting an idle link-conductor as long as the accidental ground is present. If limb 2 becomes accidentally grounded, the rotation of the switch will be started as soon as the subscriber attempts to make a call and will continue until his receiver is replaced, when the switch will then stop on the contacts of the first idle link-circuit encountered thereafter. A circuit may then be traced from the upper 25 terminal of battery C as before, through the differential windings 31 and 34 of relay 32 and through the strand 33 to wiper *b* and the winding of the cut-off relay, causing the attraction of the cut-off relay but leaving relay. 30 32 inert. The circuit now being open at the substation, no current can be supplied to energize relay 37, and relay 32 therefore continues unenergized. The current flowing through winding 34, however, serves at this 35 time to energize relay 43, causing the engagement of its armature and contact 98—97 and the illumination of lamp 51. The operator then actuates her listening-key as in answering a call, and observing that lamp 51 still 40 remains lighted has an indication of this accidental condition; she then established the regular releasing circuit by inserting her plug O into the jack of any idle line and immediately withdrawing it. When the plug is inserted the energization of relay 40 interrupts the circuit through winding 34 and relay 43 at armature 39 and contact 38. The relay 45 32 is then energized by current through its winding 31, causing armature 41 to engage contact 57 and when the plug is subsequently removed, the reengagement of armature 39 with contact 38 establishes the regular releasing circuit previously described. If the subscriber inadvertently removes his receiver and immediately replace it, an idle 50 link-circuit will be selected, and disconnected by the operator in a similar manner.

While I have described one arrangement 60 of grouping the link-conductors or cord-circuits in their relation to the various switches and to the several operators' position of a system, it is obvious that other methods of grouping may be employed and I do not, therefore, wish to be limited to the particular 65 arrangement described. Neither, in that

feature of my invention which relates to the means for making the link-circuits artificially busy, do I wish to be limited to a structure of the general character illustrated, as it is obvious that this feature of my invention 70 may be embodied in other telephone exchange systems. It is also obvious that various means may be employed for causing the rotation of the switch and its wipers; that the various grounds indicated may be 75 a common return and connected with the grounded or return side of the central battery; that the battery C' may be the same as battery C; and that various modifications and alterations of my invention may be 80 made without departing from its spirit.

What I consider as new and novel and desire to protect by Letters Patent of the United States is:

1. A telephone exchange system comprising 85 a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line 90 relay normally connected in circuit with the line limbs, line and local wipers for said switch, said local wiper being connected with a winding of the line relay, and said wipers engaging said fixed contacts when the 95 switch is operated, and a cut-off relay operating when energized to interrupt the normal circuit of the line limbs and of the line relay.

2. A telephone exchange system comprising 100 a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said 105 switch constituting terminals of line and local conductors of said link-circuits, a line relay normally connected in circuit with the line limbs, line wipers for said switch connected to the line limbs when the line relay is 110 inert and a local wiper connected with a winding of the line relay, said wipers engaging said fixed contacts when the switch is operated, and a cut-off relay operating when 115 energized to interrupt the normal circuit of the line limbs and of the line relay.

3. A telephone exchange system comprising 120 a plurality of telephone lines, a plurality of link-circuits terminating in connecting plugs at a plurality of operators' positions, a subscriber's line extending in two limbs from a substation to the exchange, a source of cur- 125

rent for the line, signal indicators for the link-circuits, a traveling switch for the line operated by a motor magnet and a source of current, fixed contacts for said switch constituting terminals of line and local conductors of said link-circuits, a line relay normally connected in circuit with the line limbs, line and local wipers for said switch, said local wiper being connected with a winding of the line relay and said wipers engaging said fixed contacts when the switch is operated, and a cut-off relay operating when energized to interrupt the normal circuit of the line limbs and of the line relay.

15 4. A telephone exchange system comprising a plurality of telephone lines, a plurality of link-circuits terminating in connecting plugs at a plurality of operators' positions, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay normally connected in circuit with the line limbs, line wipers for said switch connected to the line limbs when the line relay is inert and a local 25 wiper connected with a winding of the line relay, said wipers engaging said fixed contacts when the switch is operated, and a cut-off relay operating when energized to interrupt the normal circuit of the line limbs and 30 of the line relay.

5 5. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay, line and local wipers for said switch engaging said fixed contacts when the switch is operated, a cut-off relay operating when energized to interrupt the normal circuit of the line limbs and of the line relay, and a local winding for the line relay in a circuit controlled at one point by the cut-off relay and at another point by the local wiper.

55 6. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line

relay, switch contacts of the line relay in circuit with the winding of the motor magnet and operating when the relay is energized to complete the circuit of the motor magnet and source of current, a cut-off relay operating 70 when energized to interrupt the normal circuit of the line limbs and of the line relay, and a local winding for the line relay in a circuit controlled at one point by the cut-off relay and at another point by the local wiper. 75

7. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and 80 a source of current, fixed contacts for said switch constituting terminals of line and local conductors of said link-circuits, a line relay normally connected in circuit with the line limbs, line and local wipers for said switch engaging said fixed contacts when the switch is operated, a cut-off relay operating 85 when energized to interrupt the normal circuit of the line limbs and of the line relay, and a local winding for the line relay in a circuit controlled at one point by the cut-off relay and at another point by the local wiper. 90

8. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay normally connected in circuit with the line limbs, switch contacts of the line relay in circuit with the winding of the motor magnet and operating when the relay is energized 100 to complete the circuit of the motor magnet and source of current, a cut-off relay operating when energized to interrupt the normal circuit of the line limbs and of the line relay, and a local winding for the line relay in a circuit controlled at one point by the cut-off relay and at another point by the local wiper. 105

9. A telephone exchange system comprising a plurality of telephone lines, a plurality of link-circuits terminating in connecting 110 plugs, a subscriber's line extending in two limbs from a substation to the exchange, a source of current for the line, signal indicators for the link-circuits, a traveling switch for the line operated by a motor magnet and 115 a source of current, fixed contacts for said switch constituting terminals of line and local conductors of said link-circuits, a line relay, switch contacts of the line relay in circuit with the winding of the motor magnet 120 and operating when the relay is energized to complete the circuit of the motor magnet and source of current, a cut-off relay operating when energized to interrupt the normal circuit of the line limbs and of the line relay, and a local winding for the line relay in a circuit controlled at one point by the cut-off relay and at another point by the local wiper. 125

130

and operating when the relay is energized to complete the circuit of the motor magnet and source of current, a cut-off relay operating when energized to interrupt the normal circuit of the line limbs and of the line relay, and a local winding for the line relay in a circuit completed at the time of disconnection whereby said line relay is energized.

10. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay, switch contacts of the line relay in circuit with the winding of the motor magnet and operating when the relay is energized to complete the circuit of the motor magnet and source of current, a cut-off relay operating 25 when energized to interrupt the normal circuit of the line limbs and of the line relay, and a local winding for the cut-off relay in a circuit completed at the time of disconnection whereby the energization of the relay is maintained until the switch is in its normal position.

11. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay, switch contacts of the line relay in circuit with the winding of the motor magnet and operating when the relay is energized to complete the circuit of the motor magnet and source of current, a cut-off relay operating 40 when energized to interrupt the normal circuit of the line limbs and of the line relay, and local windings for the line and cut-off relays in a circuit through their conjoint energization and only interrupted by contacts of the switch when it is in its normal position.

12. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and

a source of current, fixed contacts for said switch constituting terminals of line and local conductors of said link-circuits, a line relay, switch contacts of the line relay in circuit with the winding of the motor magnet and operating when the relay is energized to complete the circuit of the motor magnet and source of current, a cut-off relay operating when energized to interrupt the normal circuit of the line limbs and of the line relay, and a locking circuit for the line and cut-off relays completed through the conjoint energization of said relays and interrupted by contacts of the switch when it is in its normal position.

13. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay, switch contacts of the line relay in circuit with the winding of the motor magnet and operating when the relay is energized to complete the circuit of the motor magnet and source of current, a cut-off relay operating when energized to interrupt the normal circuit of the line limbs and of the line relay, and local windings for the line and cut-off relays in a circuit through their conjoint energization and only interrupted by contacts of the switch when it is in its normal position.

14. A telephone exchange system comprising a plurality of telephone lines, a plurality of link-circuits terminating in connecting plugs, a subscriber's line extending in two limbs from a substation to the exchange, a source of current for the line, signal indicators for the link-circuits, a traveling switch for the line operated by a motor magnet and a source of current, fixed contacts for said switch constituting terminals of line and local conductors of said link-circuits, a line relay, switch contacts of the line relay in circuit with the winding of the motor magnet and operating when the relay is energized to complete the circuit of the motor magnet and source of current, a cut-off relay operating 105 when energized to interrupt the normal circuit of the line limbs and of the line relay, and local windings for the line and cut-off relays in a circuit completed through their conjoint energization and only interrupted by contacts of the switch when it is in its normal position.

15. A telephone exchange system comprising a plurality of telephone lines, a plurality of link-circuits terminating in connecting plugs, a subscriber's line extending in two limbs from a substation to the exchange, a

source of current for the line, signal indicators for the link-circuits, a pair of relays for each link-circuit, a source of current associated therewith, and a neutralizing wind-
5 ing for one of said link-circuit relays in a circuit controlled by the other of said link-circuit relays whereby, when both of said relays are included in circuit, the first-mentioned link-circuit relay will not be energized until
10 the last-mentioned link-circuit relay is operated.

16. A telephone exchange system comprising a plurality of telephone lines, a plurality of link-circuits, terminating in connecting plugs, a subscriber's line extending in two limbs from a substation to the exchange, a source of current for the line, signal indicators for the link-circuits, a traveling switch for the line operated by a motor magnet and
15 a source of current, fixed contacts for said switch constituting terminals of line and local conductors of said link-circuits, a line relay, line and local wipers for said switch engaging said fixed contacts when the switch is
20 operated, a cut-off relay operating when energized to interrupt the normal circuit of the line limbs and of the line relay, a pair of relays for each link-circuit, a source of current associated therewith, and a neutralizing wind-
25 ing for one of said link-circuit relays in a circuit controlled by the other of said link-circuit relays whereby, when both of said relays are included in circuit, the first-mentioned link-circuit relay will not be energized until
30 the last-mentioned link-circuit relay is operated.

17. A telephone exchange system comprising a plurality of telephone lines, a plurality of link-circuits, automatic switching means for establishing connection between a calling line and an idle link-circuit, a controlling relay for said switching means normally under the control of the calling party, a cut-off relay, and means for restoring said switching means to normal upon the energization of both of said relays.

18. A telephone exchange system comprising a plurality of telephone lines, a plurality of link-circuits terminating in manual connection terminals, coöperating connection terminals adapted to be connected thereto, automatic switching means for establishing connection between a calling line and an idle link-circuit, a controlling relay for said switching means normally under the control of the calling party, a cut-off relay, means for restoring said switching means to normal upon the energization of both of said relays, and means responsive to the disconnection of said manual connection terminal for causing the simultaneous energization of said relays.

19. A telephone exchange system comprising a plurality of telephone lines, a plurality of link-circuits, signal indicators for the

link-circuits, automatic switching means for establishing connection between a calling line and an idle link-circuit, a controlling relay for said switching means normally under the control of the calling party, means for actuating the appropriate signal indicator upon the establishment of such connection, a cut-off relay, and means for restoring said switching means to normal upon the energization of both of said relays.

20. A telephone exchange system comprising a plurality of telephone lines, a plurality of link-circuits terminating in manual connection terminals, coöperating connection terminals adapted to be connected thereto, signal indicators for the link-circuits, automatic switching means for establishing connection between a calling line and an idle link-circuit, a controlling relay for said switching means normally under the control of the calling party, means for actuating the appropriate signal indicator upon the establishment of such connection, a cut-off relay, means for restoring said switching means to normal upon the energization of both of said relays, and means responsive to the disconnection of said manual connection terminal for causing the simultaneous energization of said relays.

21. A telephone exchange system comprising a plurality of telephone lines, a plurality of link-circuits terminating in manual connection terminals, coöperating connection terminals adapted to be connected thereto, automatic switching means for establishing connection between a calling line and an idle link-circuit, a controlling relay for said switching means normally under the control of the calling party, means for displaying a signal upon the establishment of such connection, a cut-off relay, means for placing said signal under the calling substation control upon the connection of the manual terminal to its coöperating terminal, a second signaling means placed under the called substation control by said connection and means for restoring said switching means to normal upon the energization of both of said relays.

22. A telephone exchange system comprising a plurality of telephone lines, a plurality of link-circuits terminating in manual connection terminals, coöperating connection terminals adapted to be connected thereto, automatic switching means for establishing connection between a calling line and an idle link-circuit, a controlling relay for said switching means normally under the control of the calling party, means for displaying a signal upon the establishment of such connection, a cut-off relay, means for placing said signal under the calling substation control upon the connection of the manual terminal to its coöperating terminal, a second signaling means placed under the

called substation control by said connection, means for restoring said switching means to normal upon the energization of both of said relays, and means responsive to the disconnection of said manual terminal for causing the simultaneous energization of said relays.

23. A telephone exchange system comprising a plurality of telephone lines, a plurality of link-circuits extending to different operators' positions at the exchange, automatic switching means for establishing connection between a calling line and an idle one of said link-circuits, and means responsive to the establishment of such connection to render all other link-circuits at the particular operator's position artificially busy.

24. A telephone exchange system comprising a plurality of telephone lines, a plurality of link-circuits extending to different operators' positions at the exchange, automatic switching means for establishing connection between a calling line and an idle one of said link-circuits, means responsive to the establishment of such connection to render all other link-circuits at the particular operator's position artificially busy, and means under the control of the operator for removing said busy condition.

25. A telephone exchange system comprising a plurality of telephone lines, a plurality of link-circuits extending to different operators' positions at the exchange, automatic switching means for establishing connection between a calling line and an idle one of said link-circuits, means responsive to the establishment of such connection to render all other link-circuits at the particular operator's position artificially busy, an operator's telephone set, and means responsive upon the inclusion of said set in circuit with said link-circuit to remove said busy condition.

26. A telephone exchange system comprising a plurality of telephone lines, a plurality of link-circuits extending to different operators' positions at the exchange, automatic switching means for establishing connection between a calling line and an idle one of said link-circuits, and automatic means for rendering all other link-circuits at the particular operator's position artificially busy.

27. A telephone exchange system comprising a plurality of telephone lines, a plurality of link-circuits extending to different operators' positions at the exchange, automatic switching means for establishing connection between a calling line and an idle one of said link-circuits, automatic means for rendering all other link-circuits at the particular operator's position artificially busy, and means under the control of the operator for removing said busy condition.

28. A telephone exchange system comprising

a plurality of telephone lines, a plurality of link-circuits, an automatic switch having traveling contacts for establishing connection between a calling line and an idle link-circuit, a controlling relay for said switch, means under the control of the subscriber for energizing said relay to cause said switch to begin its operation, means for maintaining said relay energized to cause said switch to continue its operation until an idle link-circuit is encountered, means under the control of the operator to complete a circuit including a traveling contact of said switch and a winding of said relay to again energize said relay and thereby again set said switch in operation, and means for maintaining said relay energized until said switch reaches normal.

29. A telephone exchange system comprising a plurality of telephone lines, a plurality of link-circuits, an automatic switch having traveling contacts for establishing connection between a calling line and an idle link-circuit, a controlling relay for said switch, means under the control of the subscriber for initially energizing said relay to cause said switch to begin its operation, a maintaining circuit for said relay including one of the aforesaid traveling contacts, means for interrupting said circuit when an idle link-circuit is encountered, means under the control of the operator to again complete a circuit including a traveling contact of said switch and a winding of said relay to again initially energize said relay to again set said switch in operation, a maintaining circuit for said relay established upon said latter energization, and means responsive to the movements of said switch for controlling said circuit.

30. A telephone exchange system comprising a plurality of telephone lines, a plurality of link-circuits, an automatic switch having traveling contacts for establishing connection between a calling line and an idle link-circuit, a controlling relay for said switch, means under the control of the subscriber for initially energizing said relay to cause said switch to begin its operation, a maintaining circuit for said relay including one of the aforesaid traveling contacts, means for interrupting said circuit when an idle link-circuit is encountered, means under the control of the operator to again complete a circuit including a traveling contact of said switch and a winding of said relay to again initially energize said relay to again set said switch in operation, a maintaining circuit for said relay established upon said latter energization, and means for interrupting said maintaining circuit when said switch reaches normal.

31. A telephone exchange system comprising a plurality of telephone lines, a plurality of associated link-circuits, automatic

- switching means for establishing connection between a calling line and an idle link-circuit, a pair of relays associated with the selected link-circuit and having windings in circuit with the talking strands thereof, and neutralizing means acting on one of said relays and controlled by the other.
32. A telephone exchange system comprising a plurality of telephone lines, a plurality of associated link-circuits, automatic switching means for establishing connection between a calling line and an idle link-circuit, a pair of relays associated with the selected link-circuit and having windings in circuit with the talking strands thereof, and a neutralizing winding on one of said relays in a circuit controlled by the other.
33. A telephone exchange system comprising a plurality of telephone lines, a plurality of associated link-circuits, automatic switching means for establishing connection between a calling line and an idle link-circuit, a pair of relays associated with the answering end of each link-circuit, and means whereby the energization of one of said relays is dependent upon the operative condition of the other.
34. A telephone exchange system comprising a plurality of telephone lines, a plurality of associated link-circuits, automatic switching means for establishing connection between a calling line and an idle link-circuit, a pair of relays associated with the answering end of each link-circuit, one of said relays being under the control of a calling party when its link-circuit is connected to the calling line, and means whereby the energization of the other of said relays is dependent upon the condition of the first relay.
35. A telephone exchange system comprising a plurality of telephone lines, a plurality of link-circuits, automatic switching means for establishing connection between a calling line and an idle link-circuit, a pair of controlling relays, one of which is normally in circuit with a calling line, means for completing a circuit through windings of both relays to cause a restoration of the switching means to normal, a locking-circuit therefor, and means associated with said switching means to interrupt said locking-circuit when the switching means reaches normal.
36. A telephone exchange system comprising a plurality of telephone lines, a plurality of link-circuits, automatic switching means for establishing connection between a calling line and an idle link-circuit, a pair of controlling relays, one of which is a cut-off relay, means for completing a circuit through windings of both relays to cause a restoration of the switching means to normal, a locking-circuit therefor, and means associated with said switching means to interrupt said locking-circuit when the switching means reaches normal.
37. A telephone exchange system comprising a plurality of telephone lines, a group of signal indicators therefor, means operated over the lines for variously associating said lines and indicators and causing the display of the latter, and means operated during the display of any one indicator to prevent the display of any other indicator in the group.
38. A telephone exchange system comprising a plurality of telephone lines, a group of signal indicators therefor, means operated over the lines for variously associating said lines and indicators and causing the display of the latter, and connections rendering the other indicators inoperable while one is displayed.
39. A telephone system including a telephone line, a line relay therefor, a cut-off relay for operation to disconnect said line relay from the line, and means for simultaneously closing a series circuit energizing said relays including a central source of current.
40. A telephone system including a telephone line, a line relay therefor, a cut-off relay for operation to disconnect said line relay from the line and operators' means for simultaneously closing a series circuit energizing said relays including a central source of current.
41. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, and means controlled by the operator for energizing said second winding to restore said switch to normal.
42. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, means controlled by the operator for energizing said second winding to restore said switch to normal, and a connection for continuing said cut-off relay energized while said switch is restoring.
43. A telephone system including a telephone line, link-circuits at the exchange, a selective switch for said line for actuation to automatically select and connect said line with an idle link-circuit, a line relay having a winding normally in circuit with said line for actuation responsive to current there-

over to initiate travel of said switch, a cut-off relay for actuation on selection made to disconnect said winding, a second winding for said line relay, means controlled by the operator for energizing said second winding to restore said switch to normal, and a locking contact for said relay thereon effective to continue its energization while said switch is restoring.

44. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, means controlled by the operator for energizing said second winding to restore said switch to normal, a locking contact for said relay thereon effective to continue its energization while said switch is restoring, and an off-normal contact opened when the switch is restored to deenergize said relay.

45. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, means controlled by the operator for initially energizing said second winding, a locking contact for said relay thereon effective to continue its energization while said switch is restoring, and a connection for continuing said cut-off relay energized while said switch is restoring.

46. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, means controlled by the operator for initially energizing said second winding, a locking contact for said relay thereon effective to continue its energization while said switch is restoring, an off-normal contact opened when the switch is restored to deenergize said relay, and a connection for continuing said cut-off relay energized while said switch is restoring.

47. A telephone system including a telephone line, link-circuits at the exchange, a

selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, a circuit controlled by the operator for energizing said second winding in series with said cut-off relay to restore said switch, and means for continuing said relays energized independently of the operator while the switch is restoring.

48. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, a circuit controlled by the operator for energizing said second winding in series with said cut-off relay to restore said switch, means for continuing said relays energized independently of the operator while the switch is restoring, and an off-normal contact actuated on restoration of said switch to deenergize said relays.

49. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, and a circuit controlled by the operator for energizing said second winding in series with said cut-off relay to restore said switch.

50. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, and means controlled by the operator for effecting a simultaneous energization of said windings to restore said switch to normal.

51. A telephone system including a telephone line, link-circuits at the exchange, a selective switch for said line for actuation to automatically select and connect said line with an idle link-circuit, a line relay having a winding normally in circuit with said line for

- actuation responsive to current thereover to initiate travel of said switch, a cut-off relay for actuation on selection made to disconnect said winding, a second winding for said relay, means controlled by the operator for initially energizing said second winding, and a locking contact effective only when said second winding is energized to continue said relay energized.
52. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said relay, means controlled by the operator for initially energizing said second winding, a locking contact effective only when said second winding is energized to continue said relay energized, and a switch automatically shifted on restoration of said selective switch to deenergize said relay.
53. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a locking circuit for said line relay including an armature switch thereof, a normally open switch contact of said cut-off relay included in said circuit for closure on actuation of said relay, and means controlled by the operator for finally effecting completion of said locking circuit to restore said selective switch.
54. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a locking circuit for said line relay including an armature switch thereof, a normally open switch contact of said cut-off relay included in said circuit for closure on actuation of said relay, an off-normal contact of said selective switch included in said circuit for closure on initial movement of said switch, and means controlled by the operator for finally effecting completion of said locking circuit to restore said selective switch.
55. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, off-normal switch contacts, means under the control of the operator for initially energizing said second winding, and a holding circuit therefor subsequently closed through said off-normal switch contacts, whereby said line
- selective switch for said line for actuation to automatically select and connect said line with an idle link-circuit, a line relay having a winding normally in circuit with said line for actuation responsive to current thereover to initiate travel of said switch, a cut-off relay, a locking circuit for said line relay including an armature switch thereof, a normally open switch contact of said cut-off relay included in said circuit for closure on actuation of said relay, an off-normal contact of said selective switch included in said circuit for closure on initial movement of said switch, means controlled by the operator for finally effecting completion of said locking circuit to restore said selective switch, and means for automatically opening said circuit on restoration of said switch.
56. A telephone system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay, a locking circuit for said line relay including an armature switch thereof, a normally open switch contact of said cut-off relay included in said circuit for closure on actuation of said relay, an off-normal contact of said selective switch included in said circuit for closure on initial movement of said switch, means controlled by the operator for finally effecting completion of said locking circuit to restore said selective switch, a winding of said cut-off relay also included in said circuit, and means for automatically opening said circuit on restoration of said switch.
57. A telephone exchange system comprising a plurality of telephone lines, a group of electrically operated indicators therefor, means controlled over the lines for closing the operating circuits of said indicators to cause their display, and means operated during the display of any one indicator to prevent the closing of the operating circuit of any other indicator in the group.
58. A telephone exchange system including a telephone line, link-circuits at the exchange, a selective switch for said line for actuation to automatically select and connect said line with an idle link-circuit, a line relay having a winding normally in circuit with said line for actuation responsive to current thereover to initiate travel of said switch, a cut-off relay for actuation on selection made to disconnect said winding, a second winding for said line relay, off-normal switch contacts, means under the control of the operator for initially energizing said second winding, and a holding circuit therefor subsequently closed through said off-normal switch contacts, whereby said line

relay is maintained energized until said switch reaches normal.

59. A telephone exchange system including a telephone line, link-circuits at the exchange, automatic switch mechanism for uniting said line and an idle link-circuit, said mechanism having one normal position to which it is restored after operation, a starting relay for said mechanism normally controlled over said line, a cut-off relay for destroying said normal control, means controlled by said starting relay to restore said mechanism to normal, and operator's means for operating said starting relay to bring about such restoration.

60. A telephone exchange system including a telephone line, link-circuits at the exchange, automatic switch mechanism for uniting said line and an idle link-circuit, said mechanism having one normal position to which it is restored after operation, a starting relay for said mechanism normally controlled over said line, a cut-off relay for destroying said normal control, means controlled by said starting relay to restore said mechanism to normal, a circuit under operator's control for initially actuating said starting relay, and means for continuing it actuated until said mechanism reaches normal.

61. A telephone exchange system including a telephone line, link-circuits at the exchange, automatic switch mechanism for uniting said line and an idle link-circuit, a starting relay for said mechanism normally controlled over said line, a cut-off relay for destroying said normal control, means controlled by said starting relay to restore said mechanism to normal, a circuit under operator's control for initially actuating said starting relay and for maintaining said cut-off relay operated, and means for completing

a subsequent circuit for said relays and maintaining it until said mechanism reaches normal.

62. A telephone exchange system including a telephone line, link-circuits at the exchange, automatic switch mechanism for uniting said line and an idle link-circuit, a starting relay for said mechanism normally controlled over said line, a cut-off relay for destroying said normal control, means controlled by said starting relay to restore said mechanism to normal, off-normal contacts on said switch mechanism, a circuit under operator's control for initially actuating said starting relay, and means for closing a subsequent circuit for said relay through said off-normal contacts, whereby said mechanism is kept operating until it reaches normal, whereupon it comes to rest.

63. A telephone exchange system including a telephone line, link-circuits at the exchange, automatic switch mechanism for uniting said line and an idle link-circuit, a starting relay for said mechanism normally controlled over said line, a cut-off relay for destroying said normal control, means controlled by said starting relay to restore said mechanism to normal, off-normal contacts on said switch mechanism, a circuit under operator's control for initially actuating said starting relay and for maintaining said cut-off relay operated, and means for closing a subsequent circuit for said relays through said off-normal contacts, whereby said mechanism is kept operating until it reaches normal, whereupon it comes to rest.

In witness whereof, I hereunto subscribe my name this 25th day of July 1906.

HARRY G. WEBSTER.

Correction in Letters Patent No. 931,904.

It is hereby certified that in Letters Patent No. 931,904, granted August 24, 1909, upon the application of Harry G. Webster, of Chicago, Illinois, for an improvement in "Telephone Systems," an error appears in the printed specification requiring correction, as follows: On page 3, lines 3-4, "and armature 39 of relay 40," should be stricken out; and that the said Letters Patent should be read with this correction therein that the same may conform to the record of the case in the Patent Office.

Signed and sealed this 5th day of October, A. D., 1909.

[SEAL.]

C. C. BILLINGS,
Acting Commissioner of Patents.

relay is maintained energized until said switch reaches normal.

59. A telephone exchange system including a telephone line, link-circuits at the exchange, automatic switch mechanism for uniting said line and an idle link-circuit, said mechanism having one normal position to which it is restored after operation, a starting relay for said mechanism normally controlled over said line, a cut-off relay for destroying said normal control, means controlled by said starting relay to restore said mechanism to normal, and operator's means for operating said starting relay to bring about such restoration.

60. A telephone exchange system including a telephone line, link-circuits at the exchange, automatic switch mechanism for uniting said line and an idle link-circuit, said mechanism having one normal position to which it is restored after operation, a starting relay for said mechanism normally controlled over said line, a cut-off relay for destroying said normal control, means controlled by said starting relay to restore said mechanism to normal, a circuit under operator's control for initially actuating said starting relay, and means for continuing it actuated until said mechanism reaches normal.

61. A telephone exchange system including a telephone line, link-circuits at the exchange, automatic switch mechanism for uniting said line and an idle link-circuit, a starting relay for said mechanism normally controlled over said line, a cut-off relay for destroying said normal control, means controlled by said starting relay to restore said mechanism to normal, a circuit under operator's control for initially actuating said starting relay and for maintaining said cut-off relay operated, and means for completing

a subsequent circuit for said relays and maintaining it until said mechanism reaches normal.

62. A telephone exchange system including a telephone line, link-circuits at the exchange, automatic switch mechanism for uniting said line and an idle link-circuit, a starting relay for said mechanism normally controlled over said line, a cut-off relay for destroying said normal control, means controlled by said starting relay to restore said mechanism to normal, off-normal contacts on said switch mechanism, a circuit under operator's control for initially actuating said starting relay, and means for closing a subsequent circuit for said relay through said off-normal contacts, whereby said mechanism is kept operating until it reaches normal, whereupon it comes to rest.

63. A telephone exchange system including a telephone line, link-circuits at the exchange, automatic switch mechanism for uniting said line and an idle link-circuit, a starting relay for said mechanism normally controlled over said line, a cut-off relay for destroying said normal control, means controlled by said starting relay to restore said mechanism to normal, off-normal contacts on said switch mechanism, a circuit under operator's control for initially actuating said starting relay and for maintaining said cut-off relay operated, and means for closing a subsequent circuit for said relays through said off-normal contacts, whereby said mechanism is kept operating until it reaches normal, whereupon it comes to rest.

In witness whereof, I hereunto subscribe my name this 25th day of July 1906.

Correction in Letters Patent No. 931,904.

It is hereby certified that in Letters Patent No. 931,904, granted August 24, 1909, upon the application of Harry G. Webster, of Chicago, Illinois, for an improvement in "Telephone Systems," an error appears in the printed specification requiring correction, as follows: On page 3, lines 3-4, "and armature 39 of relay 40," should be stricken out; and that the said Letters Patent should be read with this correction therein that the same may conform to the record of the case in the Patent Office.

Signed and sealed this 5th day of October, A. D., 1909.

[SEAL.]

C. C. BILLINGS,
Acting Commissioner of Patents.

DISCLAIMER.

931,904.—*Harry G. Webster*, Chicago, Ill. TELEPHONE SYSTEM. Patent dated August 24, 1909. Disclaimer filed March 8, 1915, by *Kellogg Switchboard and Supply Company*, assignee, by mesne assignments.

Enters its disclaimer—

“To the claims of the patent, which read as follows, to wit:

“33. A telephone exchange system comprising a plurality of telephone lines, a plurality of associated link-circuits, automatic switching means for establishing connection between a calling line and an idle link-circuit, a pair of relays associated with the answering end of each link-circuit, and means whereby the energization of one of said relays is dependent upon the operative condition of the other.

“34. A telephone exchange system comprising a plurality of telephone lines, a plurality of associated link-circuits, automatic switching means for establishing connection between a calling line and an idle link-circuit, a pair of relays associated with the answering end of each link-circuit, one of said relays being under the control of a calling party when its link-circuit is connected to the calling line, and means whereby the energization of the other of said relays is dependent upon the condition of the first relay.”
